MATCHED POTENTIAL ELECTRICAL
CONTROL SYSTEM

Henry F. Herbig, Summit, N. J., assignor to International Standard Electric Corporation, New York, N. Y., a corporation of Delaware

Application July 7, 1945, Serial No. 603,687

6 Claims. (Cl. 179—18)

1

This invention relates to electrical control systems in which a controlled device is actuated when a potential applied to the system at a control station is matched by a potential applied to the system at an operating station. It is particularly applicable to automatic telephone systems, but may be used in control systems and especially remote control systems of various types, such as electric elevator control, gun control, calculating machines, telegraph, ticket and other automatic printers and the like.

The invention includes in general an actuating device that will not operate when one of the applied potentials is below a cut-off value relative to the other potential, in combination with means for preventing operation of the control device by the actuating device when said first potential is above a selected value in the operating range of the actuating device, as by disconnecting said device. With this arrangement the controlled device is actuated only when the first potential is between said values, a relationship referred to herein as matching.

More specifically, the invention includes the use of a vacuum tube in the actuating device, the station potentials, or potentials derived from them, being applied to the control grid and cathode of the tube, the controlled device being operated by anode current which flows whenever the potential of the control grid relative to the cathode is above the cut-off value, in combination with means for disconnecting the anode from the controlled device when such relative grid potential is higher than a predetermined value above cut-off.

A feature of the invention is the utilization of a vacuum tube having a screen grid to provide a simplified control system. In screen grid tubes of the appropriate type an increase in the control grid potential above the cut-off value produces not only progressively increasing anode current up to the saturation point but also progressively increasing screen grid current, which however is only a rather small fraction of the anode current. The invention includes the utilization of this tube characteristic to obtain the results already described by employing the system connected to the screen grid and anode, including means operated by the anode current only when the screen grid current is below a predetermined value. With this arrangement the system will not be operated when the control grid is at a cut-off value below which useful anode current is not generated and likewise will be inoperative when the screen grid current is above said value, even though sub-

stantial anode current is simultaneously generated.

This is advantageously accomplished by employing a current responsive actuating device, such as a relay, in the anode circuit of the tube and a second current responsive device, such as a relay, in the screen grid circuit which when actuated by the screen grid current will cut out the first device. The second device is selected so that the screen grid current will be insufficient to operate it when the control grid potential relative to the cathode is within the matching range.

The invention is especially advantageous when utilized in an automatic telecommunication system in which a register at the control station is provided with a brush moved over a series of contact points maintained at different potentials and a selector at the operating station is provided with a brush moved over a similar series of contact points. The purpose is to halt the selector brush on a contact point whose potential matches that of the point on which the register brush has been stopped. If the appropriate point is idle during the first passage of the selector brush the latter will be halted as soon as it reaches such point; but if the latter is busy its potential will be changed and the selector brush will continue to hunt, as set forth in Patent No. 2,380,950 of Gerald Deakin, and in the various applications and patents referred to therein, this invention being a modification of the control circuits disclosed therein.

Other features and advantages of the invention will appear from the following description considered in connection with the accompanying drawing, which is a diagram of as much of a control system as is necessary for a clear understanding of the present invention.

The drawing illustrates the application of the invention to an automatic telephone system in which calling and called subscribers' stations 1 and 2 may be interconnected by means including a plurality of selector switches 3 and 4. The numerical operations of the selectors are controlled by the calling subscriber's customary impulse 40 sender, key sender or other common form of control device through the agency of a register provided at the central exchange. The calling station 1 is connected to the brushes of selector 3 by known switches (not shown) and a connecting circuit 5, and the register is attached to the connecting circuit 5 through switching means 6.

The selector switches are of the customary type, having a bank of terminals with which a set of brushes cooperates. In the drawings three brushes are shown for selector switch 3, the low-

ermost being designated as T, although the selector may have a larger number of brushes. The selector brushes are moved over the selector terminals ST while a magnet P is energized, and are stopped on a set of terminals when this magnet becomes deenergized, this construction and operation being well known.

The register comprises a series of switches successively operable by the calling device in accordance with successive digits of the called number which are dialed by the calling subscriber. Brush RB and a set of terminals RT of one of these register switches are illustrated. This is the register switch which responds to the digit in accordance with which the illustrated selector 3 is to be set. When brush RB is advanced toward one of its ten terminals in accordance with the operation of the calling device at station 1, the relay AR 1 having been energized in the customary manner, a circuit is closed from ground over the right armature and its front contact of relay AR 1, the armature and back contact of register relay VR, the winding of selector relay AR and the magnet P to grounded battery. Magnet P is energized and the brushes of selector switch 3 are driven over the selector test terminals ST continuously in known manner until relay VR is energized and breaks the circuit of magnet P.

The circuit of relay VR extends from the anode of tube V through the back contact and armature of relay PCR, the winding of relay VR and the left front armature and front contact of relay AR 1 to grounded high tension battery HTB 1. The winding of relay VR may be shunted by resistor R 5 if necessary to obtain the desired operation. The circuit of the winding of relay PCR extends from the screen grid of tube V through the back left armature and its front contact of relay AR 1 to grounded high tension battery HTB 2.

Each of the register terminals RT is connected through a suitable resistor to a source of potential, and the selector terminals ST are similarly connected, the potentials of successive terminals advantageously varying progressively by the same amount, which in the illustrated embodiment is four volts, though it will be understood that this particular potential arrangement may be varied within the scope of the invention. Either a series of negative potentials or a series of positive potentials may be employed as indicated.

The register brush RB is connected to the cathode of tube V and the selector brush T is connected to the control grid of the tube, preferably through a biasing resistor R 2. Brush T is advantageously connected through a high value resistor R 4 to the negative terminal of grounded battery, in order to prevent false operation when the brush T is not in contact with a terminal ST. With this arrangement the potential of the register terminal RT selected by brush RB will be applied to the cathode of tube V, and the potentials of the selector terminals ST will be successively applied to the control grid of the tube with an appropriate potential drop across resistor R 2. When the control grid potential relative to the cathode potential is more negative than the value at which sufficient anode current to operate relay VR will flow, a value which will be referred to as the cut-off value, magnet P will remain in operation and the brush T will continue to travel over the terminals ST. When the

potential of the contacted terminal ST is above the minimum value at which the potential applied to the control grid will produce sufficient screen grid current to operate relay PCR, the circuit of relay VR will be opened and brush T will continue to travel over the associated terminals ST. However, when the terminal ST engaged by brush T has a potential matching the terminal T engaged by brush RB, relay VR will be energized while relay PCR remains inoperative due to the insufficient screen current generated at the applied matching potentials. The resultant shift of the armature of relay VR will open the circuit of magnet P and halt brush T on the appropriate selector terminal ST.

In the preferred arrangement illustrated, the matching terminals will normally have the same potential, but the system will be operative even though the conditions actually encountered in practice may introduce slight variations in potential between the two selected terminals, as long as the relative potentials are within the matching range. The system will also be operative where the matching potentials are substantially different by employing means such as a suitable resistor to bring the potentials into the desired relationship before applying them to the control grid and cathode of the tube. The resistor R 2 may also be utilized where the matching potentials are substantially the same to produce the control grid bias requisite for most efficient operation of certain tubes.

It will be understood that the invention has been illustrated without complicating it by the inclusion of other parts of the automatic telephone system in which it may be used, an embodiment of which is illustrated in the above-mentioned Deakin application. Certain features which might be added to adapt the illustrated arrangement to particular uses, to produce particular types of operation or to adapt the circuit to tubes having different characteristics have likewise been omitted, since the use of such features under appropriate conditions will be apparent to those skilled in the art.

Moreover, while the illustrated embodiment is especially adapted for use in automatic telephone systems, and in particular the relay system actuated by the anode current of the tube is of a type suitable for use in such systems, it will be apparent that other types of controlled devices may be actuated by the anode current. Likewise, different arrangements for selecting and applying the potentials to the two sides of the switching system may be employed, though the disclosed arrangement has particular advantage when used with automatic telephone systems including a selector and register, or corresponding arrangements.

What is claimed is:

1. An electrical control system comprising a vacuum tube having a cathode, a control grid, a screen grid and an anode, means for varying the potential of the control grid relative to the cathode potential, and control means connected to the screen grid and anode and operated by the anode and screen grid currents only when the anode current is above a predetermined value and the screen grid current is below a predetermined value.

2. A system as set forth in claim 1 in which the control means includes an actuating device operated by the anode current and means for rendering the actuating device ineffective, oper-

ated by screen grid current above a predetermined value.

3. A system as set forth in claim 1 in which the control means includes a relay connected to the anode and energized by anode current, and a cut-out relay connected to the screen grid and energized by screen grid current, an armature and back contact of the cut-out relay being located in the first relay circuit, arranged so that the first relay will be energized only when the anode current is above a predetermined relay operating value and the screen grid current is below a predetermined relay operating value.

4. An electrical control system comprising a first source of potential, a second source of potential, means for varying one potential and means for arresting said variation when the potentials are matched, comprising a vacuum tube having a cathode, a control grid, a screen grid and an anode, means for applying potentials from said sources to the cathode and control grid respectively, and an arresting system connected to the screen grid and anode including means operated by the anode current only when the anode current is above a predetermined value and the screen grid current is below a predetermined value.

5. An electrical control system comprising a first source of potential, a second source of potential, means for varying one potential and means for arresting said variation when the potentials are matched, comprising a vacuum tube having a cathode, a control grid, a screen grid and an anode, means for applying potentials from said sources to the cathode and control grid, an elec-

trically operated arresting device, a control relay having an armature and associated back contact in circuit with the arresting device and a winding connected to the anode and energized by anode current above a predetermined value, and a cut-out relay having an armature and associated back contact in circuit with the anode and control relay winding, and a winding connected to the screen grid and energized by screen grid current above a predetermined value, arranged to deenergize the arresting device only when the anode current is above the former value and the screen grid current is below the latter value.

5 6. A system as set forth in claim 5 in which the means for varying one potential includes a series of contacts at different potentials, a brush and means for driving the brush into successive engagement with the contacts, and the arresting means comprises means for rendering the driving means ineffective.
